Ship Building

N° 11,410

Patented Aug. 1, 1854.

UNITED STATES PATENT OFFICE.

HENRY C. DEPUTY, OF MICHIGAN CITY, INDIANA.

DRAFTING AND MODELING VESSELS.

Specification of Letters Patent No. 11,416, dated August 1, 1854.

To all whom it may concern:

Be it known that I, HENRY C. DEPUTY, of Michigan City, in the county of Laporte, in the State of Indiana, have invented a new 5 and Improved Mode of Drafting and Modeling Vessels of all Kinds Propelled by Sails, Steam, or Any other Power; and I do hereby declare that the following is a full and exact description thereof. (See the accompanying drawings and explanation thereon.)

The nature of my invention consists in drafting and modeling vessels of all kinds by rule (after the general outlines are given) which will produce a perfect and superior 15 shape, for speed, beauty, and sea qualities, taking off, and leaving on every inch necessary.

To enable others skilled in the art to make use of my invention, I will proceed to 20 describe the principle. First; I draft my dead-flat frame (marked thus O) in any of the known forms, and then run diagonals from equal divisions around the dead flat frame from the floor head to the bottom 25 of the wale to equal divisions from a reverse angle of the floor up the stem to the bottom of the wale. I ascertain the bottom of the wales by a parallel line with the top of the bulwark, waist, and wale, if they 30 are to be of a width; if not, then accordingly; other upper streaks—such as port streak—may be run the same way. The length of these diagonals I transfer to the O of a half breadth plan, and strike right 35 angle sweeps from those diagonal settings off to intersect the diagonal endings up the stem, then I transfer back to the body plan the intersection of those sweeps with the several different frames, which gives the 40 shape of each frame in the body plan. The stern in the same manner if the same shape on the top (or sharp) if not as the bow but square, or semielliptic; the rule varies—when it comes in contact with these shapes, 45 viz., the shear line intersects the after perpendicular at a greater height than in the

fore body. The distance from the after perpendicular (or stern post) on the diagonals to the intersecting the transom must be deducted from the whole length of said diagonals in order to find the ending of those diagonals. Also the reverse angle of the floor is raised to a parallel with the first division of diagonals; this is for a transom of $\frac{2}{3}$ the beam and $\frac{2}{3}$ floor. Then I set off 50 the intersecting of the water lines (in the body plan) with each frame to a half breadth plan which is seen in the drawing (the one with the fewest sweeps) which gives the shape of each piece in the model 55 before putting them together. The pieces in the fore body model are shaped by the above rule—it also shows the exact concavity of concave water lines—or I can apply patterns struck by those diagonal sweeps to a 60 solid, or to a pieced model, being careful to apply them correctly. The general outlines need to be good, as much so as in a frame building. Then this rule may be depended upon, as much as the square rule in framing 65 a house. A vessel may be drafted to a certainty without a model. What I term 70 general outlines, are the length, beam, depth, shear, stem and stern, and the shape and location of the dead flat frame. A knowledge of this system will facilitate ship building especially where perfection is required. 75 What I claim as my invention and desire to secure by Letters Patent, is—

The application of diagonals to drafting 80 and modeling all kinds of vessels, propelled by sails, steam or otherwise. Also the principle by which the exact concavity of concave water lines is determined, viz., by transferring the intersections of the water lines 85 (in the body plan) with each frame to a half breadth plan which is seen in the drawing (the one with the fewest sweeps).

HENRY C. DEPUTY.

Signed in presence of—

I. S. BIGELOW,
W. BAKER.
